UNITED STATES PATENT OFFICE.

CHARLES EHRENFIELD, OF PASADENA, CALIFORNIA.

FASTENING DEVICE FOR IMPLEMENTS.

SPECIFICATION forming part of Letters Patent No. 764,283, dated July 5, 1904.

Application filed October 21, 1903. Serial No. 177,905. (No model.)

To all whom it may concern:

Be it known that I, CHARLES EHRENFIELD, a citizen of the United States, residing at Pasadena, in the county of Los Angeles and State of California, have invented a certain new and Improved Fastening Device for Implements, of which the following is a specification.

My invention relates to means for holding implements on their handles--such, for instance, as picks, broadaxes, adzes, and other tools or implements having a separate handle or handles formed separate from the body portion or head of the implement.

The object of the invention is to provide simple, cheap, and durable means by which such an implement may be positively affixed on its handle.

A further object of the invention is to provide such means in such form that if the handle becomes worn in the eye of the implement-head the handle may be readily adjusted therein to take up such wear.

With these and such other objects and ends in view as hereinafter appear from the detailed description of construction the invention consists in general in an implement embodying a head having an eye or socket for the reception of the end of the handle, a retaining jaw or jaws operating in connection with said socket, and means for clamping said jaws on said handle, thereby preventing the movement of the handle in the socket or eye of the head of the implement and in effect forming a continuation of such eye or socket.

The invention will be more readily understood by reference to the accompanying drawings, forming part of this specification, in which—

Figure I is a side view of a pick provided with means fastening the handle in place embodying my invention. Fig. II is a longitudinal sectional view thereof. Fig. III is a side view of a slightly-modified form. Fig. IV is a longitudinal section view thereof. Fig. V is another slightly-modified form, the pick herein shown being the same pick used in street-work, while the picks shown in Figs. I and II are miners' picks. Fig. VI is a front elevation of a street-pick equipped with my invention. Fig. VII is a longitudinal sectional view

of the device shown in Fig. V. Fig. VIII is a longitudinal sectional view of the device shown in Fig. VI. Fig. IX is a longitudinal sectional view of an implement provided with fastening means embodying my invention, the same being shown in slightly-modified form. Fig. X is a sectional view on the line X-X in Fig. I. Fig. XI is a perspective view of one of the jaws detached, showing the form of jaw used in Fig. I. Fig. XII is a perspective view of one of the jaws detached as the same is used in the device of Fig. III. Fig. XIII is a perspective view of one of the jaws of Fig. VIII. Fig. XIV is a plan view of the clamping-rings or fasteners used with the device of Fig. I. Fig. XV is a perspective view of a modified form of jaw.

In Fig. I, I have illustrated my invention as applied to a miner's pick and in Fig. V as applied to the ordinary pick for street use. As shown in Fig. I, 2 represents the pick provided with a central head 3, having a central socket into which the end of the handle 4 is driven from the rear side, the head 3 being inwardly extended to form a good bearing for the end of the handle. In this form of my invention the head 3 is flared at its sides, so that the central opening in the head provides sockets in which the clamping-jaws rest. The clamping-jaws 5 extend along the sides of the handle 4 and up into the sockets formed by the flared portions 6 of the head, the outer ends of the jaws 5 being outwardly turned to form projections 7, adapted to extend through holes in the flared portions 6 of the head, the inner ends of the jaws 5 being provided with in-turned projections 8, adapted to fit into recesses made in the handle. 9 represents a clamping-ring having a smooth inner periphery and adapted to be slipped over the end of the handle 4 and driven up over the jaws 5 and to clamp the same in place.

The invention as illustrated in Fig. III differs from the form of Fig. I in that the head 3 is of the ordinary form, not being provided with the flared portion 6, the jaws being outwardly flared toward their upper ends, so that they extend over a portion of the head and have in-turned ends 10, Fig. IV, adapted to be inserted through holes provided in the head.

In this form the clamping-ring 9 remains the same.

- As illustrated in Figs. V and VI, the invention is applied to an ordinary pick used in streetwork, in which the socket is tapered, so that the handle is tapered and slipped through the head, and the taper of the handle forms the ordinary means for holding the pick-head in place. With this form of pick I may use either adaptation of my invention, the clamping-ring 9 remaining identical and the jaws 5 being of the form shown in Fig. I or having two branches, as shown in Fig. V, and flared outwardly and then extending inwardly and inturned to provide projections 10, adapted to fit in holes 11, provided in the head of the pick. This construction being similar to that shown in Fig. IV or as shown in Figs. VI and VIII, the head of the pick may be provided with outwardly-flared portions 12, forming sockets in which the jaws 5 may rest, the out-turned ends of the jaws fitting in sockets in the flared portion of the head, thus embodying the adaptation shown in Fig. I.
- In Fig. IX, I have shown another adaptation of my invention. With this form the jaws 5 may be either of the forms shown in Figs. II or IV; but instead of using the clamping-ring 9 I provide the jaws with the elongated slots 13 and clamp the same together on the handle by means of a bolt 14, passing through the handle, the head 15 of the bolt bearing against one of the jaws and the nut 16 bearing against the other jaw. With this construction any wear may be readily taken up.

In place of providing the jaws 5 with shanks or projections 7 or 10 I may make the upper ends thereof wedge-shaped, as shown in Fig. XV, so that as the jaws are slipped through the sockets formed by the offsets or flanged portions 6 of the head and pulled downward therein the same wedge therein. I provide the outer surfaces of the lower ends of the jaws with serrations, so that the spring-rings 9 are held from slipping by springing into the serrations.

As shown in Figs. II and IV, the serrated shanks of the jaws are tapered away from the head of the tool, so that the resilient clamping-ring 9 may be driven over the shanks as far as is necessary to hold them tightly in place.

What I claim, and desire to secure by Letters Patent of the United States, is—

1. The combination with an implement-head, provided with a socket adapted to re-

ceive a handle, of a handle therefor, jaws having projecting ends taking into said head, the shanks of said jaws having tapered portions extending out on the handle and provided at their ends with means adapted to take into said handle, and a clamping-ring adapted to spring over the tapered portions of said shanks to hold said jaws in place.

2. A fastening device for implement-handles comprising in combination with the implement-head, provided with a socket in which the handle is received, of a handle therefor, jaws embracing said head and extending from said head onto said handle, said jaws provided with means for engaging said handle, and with serrated tapered outer surfaces, and a resilient clamping-ring adapted to encircle said jaws and handle to hold said jaws in place.

3. The combination, with an implement-head provided with a socket adapted to receive a handle, of a handle therefor, jaws having projecting portions taking into said head, the shanks of said jaws provided with means for engaging said handle, said shanks tapered from said head and provided with serrations, and a resilient ring adapted to embrace said shanks and spring into said serrations.

4. The combination, with an implement-head provided with a socket adapted to receive a handle, of a handle therefor, jaws having projections taking into said head, the shanks of said jaws having serrated outer portions extending out on the handle and provided at their ends with means adapted to take into said handle, and a clamping-ring adapted to embrace said shanks and spring into said serrations.

5. The combination, with an implement-head provided with a socket adapted to receive a handle, of a handle therefor, jaws having projections taking into said head and handle, the shanks of said jaws extending out on the handle and tapered, a resilient ring having a smooth inner periphery and adapted to be driven over the taper, and means for holding the ring from slipping.

In testimony whereof I have signed my name to this specification, at Los Angeles, in the county of Los Angeles and State of California, in the presence of two subscribing witnesses, this 12th day of October, 1903.

CHARLES EHRENFIELD.
